US00D665264S

(12) United States Design Patent
Kerr et al.

(10) Patent No.: US D665,264 S
(45) Date of Patent:  Aug. 14, 2012

(54) PET FOOD SUPPLEMENT PACKAGE

(75) Inventors: George Scott Kerr, Mason, OH (US);
Gregory Dean Sunvold, Lewisburg, OH (US); Lawrence Andrew Schumacher, Trenton, OH (US); David William Schuller, Lebanon, OH (US); Robbert H Ter Haar, Dayton, OH (US); Gary J Kohlman, Terrace Park, OH (US)

(73) Assignee: The Procter & Gamble Company, Cincinnati, OH (US)

() Term: 14 Years

(21) Appl. No.: 29/414,089

(22) Filed: Feb. 24, 2012
